UNITED STATES PATENT OFFICE.

THOMAS C. ERSKINE, OF COLUMBUS, OHIO, ASSIGNOR TO UNITED SHOE MACHINERY CORPORATION, OF PATERSON, NEW JERSEY, A CORPORATION OF NEW JERSEY.

MANUFACTURE OF SHOES.

Application filed October 15, 1924. Serial No. 743,806.

This invention relates to improvements in the manufacture of shoes, and it has special reference to the construction of shoe bottoms and to methods of making and assembling shoe bottoms.

The appearance of a shoe having a wooden heel depends very largely upon the positioning of the heel with respect to the sole and the closeness of the joint between the heel and the sole. The heel-seat of a leather sole is commonly prepared for the reception of a wooden heel by an operation known as heel-seat fitting, in which the periphery of the rear end of the sole is trimmed or beveled off to provide a convex heel-seat surface adapted to coact with the concave heel-seat surface of the heel so that the heel seats firmly with the periphery of the heel-seat portion of the heel in close contact with the upper. A transverse cut is made in the sole at the heel breast line, which is commonly located by positioning the heel upon the sole, and the breast of the heel bears against the shoulder formed by this transverse cut. The accuracy of the joint between the breast of the heel and the shank of the sole is dependent in a large measure on the accuracy of the workman in making the transverse cut and especial difficulty is found in producing a sufficiently tight joint between the breast of the heel and the shank of the sole so that no crack appears between the two. Further difficulty is experienced in locating the forward corners of the heel laterally with respect to the sole so that the sides of the heel coincide exactly with the edges of the shank of the sole.

An object of the present invention is to provide an improved method of manufacturing shoes which will produce a perfect joint between the heel and the sole without requiring excessive skill by the operator. For the fulfillment of this object, considering the invention in one aspect, notches having upright corners are formed in the heel-seat end of a sole adjacent to the heel breast line adapted to co-operate with the lateral outside corners of the breast of the heel to locate the heel with respect to the sole. Preferably this operation is performed before the shank of the sole is trimmed, and consequently a perfect conjunction of the lateral edges of the sole and the sides of the heel may be obtained during the trimming operation.

In another aspect, the invention comprises providing a sole with a tongue having a portion adjacent to the heel breast line which extends the full width of the heel breast and a portion projecting toward the rear end of the shoe of lesser width. Preferably, this tongue is as thick as the shank of the sole and is an integral continuation thereof. The heel-seat of the illustrated sole at the rear of the tongue is formed by beveling the rear end of the sole substantially as before. Each lateral edge of the tongue preferably forms one side of one of the heel breast locating notches. The wooden heel which is to be applied to a sole, made as above described, is provided with a recess in its attaching face adjacent to the breast of the heel shaped complementally to the outline of the tongue and extending deeper into the heel than does the normal concavity thereof. Preferably the depth of this recess is slightly less than the thickness of the tongue upon the sole. When therefore the heel is assembled with the sole by inserting the forward corners of the heel in the notches above described, the recessed end of the heel adjacent to the breast surface overlies the tongue upon the sole and, as the heel is pressed against the sole and secured in position, it bears against this tongue and forms a tight joint between the breast surface of the heel and the surface of the shank of the sole.

In another aspect, the invention consists in a shoe bottom comprising an untrimmed sole and a finished heel, in which the sole is provided with a tongue constructed as above described and with lateral extensions in the untrimmed edges of the sole adjacent to the sides of said tongue to form notches at the heel breast line. The shoe heel constituting part of the shoe bottom is provided with a recess shaped as above described.

These and other features of the invention will be best understood from a consideration of the following specification taken in connection with the accompanying drawings in which:

Fig. 1 is a longitudinal section of the rear portion of a shoe, constructed in accordance with my invention, mounted upon a last;

Fig. 2 is a perspective view of the heel-seat of a shoe constructed in accordance with my novel method;

Fig. 3 is a perspective view of an inverted

heel recessed for co-operation with the heel-seat of the shoe shown in Fig. 2; and

Fig. 4 is a plan view of the shoe bottom, indicating by dotted lines the contour of 5 the sole of the shoe at the time the heel is attached.

After a shoe such as is indicated at 10 has been formed upon a last 12 and an outer sole 14 has been attached, a heel-seat 10 is formed in the outer sole by cutting it transversely adjacent to untrimmed edges 16 of the shank 18 of the sole 14 to provide notches 20 having upright corners, which are spaced apart the distance between 15 the lateral surfaces of the heel and are properly located with respect to the sides of the shoe so that when the heel is attached, the breast corners of the heel may be inserted in said notches to insure the exact location of 20 the heel upon the shoe with respect to the median line of the sole. The untrimmed edges of the shank provide surplus material forming extensions 21 which cooperate with the central portion of the sole to provide the 25 notches 20 and are removed when the sole edges are trimmed. In connection with the formation of the notches 20, a rearwardly extending tongue 22 is formed upon the sole which tongue is of the full thickness of the 30 shank of the sole and constitutes an integral extension thereof. The extensions 21 provide the outer sides of the notches 20 while the lateral sides of the tongue form the inner sides of said notches. This tongue 35 22, at a transverse line adjacent to the bottoms of the notches 20 coinciding with the position of the heel breast line, is of substantially the full width of the finished sole. The configuration of the tongue is not necessarily curved exactly like that shown in 40 the drawings. The trimming of the peripheral portion of the rear end of the sole is effected either manually or mechanically to bevel the sole and provide a convex heel-seat 45 24 adjacent to and extending rearwardly from the tongue 22. It will be observed later that it is not necessary for a proper assembling of the shoe or for accurate results that the vertical surface 26 of the tongue 50 shall be in a plane exactly perpendicular to the shank as is necessary in the former method of manufacture when the breast surface of the heel is perpendicular to the shank, and it is not necessary that the shape of the 55 tongue shall conform more than approximately to the shape of the recess in the heel. A wooden heel suitably formed for attachment to the sole of a shoe shaped in accordance with the features above described is 60 illustrated in Fig. 3 and will be seen to be concaved at 28 as usual and to be provided with a recess 30 curved in contour like the curvature of the tongue 22, the wall 32 of said recess preferably intersecting the lateral 65 surface 34 of the heel at the breast corners

36. Commonly a wooden heel of this type will be provided with a cover 38 of leather or cloth or celluloid and a toplift 40 which may be attached in any desired fashion as by means of a screw 42. When a heel of 70 this construction is assembled upon the sole of the shoe, the bottom 44 of the recess 30 will bear against the tongue 22 and serve to hold the shank of the sole tightly in engagement with the upper and to support the 75 portion of the sole adjacent to the notches 20 across the entire width of the finished sole so that there will be no separation of the sole from the upper at this point. In addition it will be observed that a corner 46 between 80 the breast surface of the heel and the bottom 44 of the recess will bear against the shank of the sole and the heel in such a fashion, as a result of the slightly less depth of the recess compared with the thickness 85 of the tongue 22, that when the heel is temporarily tightly clamped against the sole, for example by means of its screw fastener 48 passing through the last into the heel, and later permanently fastened in this position, the corner 46 is forced to engage closely with the shank of the sole and absolutely prevent any separation or crack between the two.

It will be observed then that the notches 20 constitute means for exactly locating the heel both laterally and longitudinally upon the shoe so that, prior to the permanent attachment of the heel to the shoe, the forward end of the heel is positioned with its outside breast corners 36 formed by the intersection of the breast surface with the lateral surface 34 coinciding with the sides of the upper. After the heel has been attached the shank will be trimmed to remove 105 the surplus material constituting the extensions 21 which are indicated by lines in Fig. 4. It will also be seen that the edges of the shank of the sole are held tightly against the upper without the necessity of 110 using metallic fasteners at this point, as is frequently done to hold down the corners of the shank left free by the removal of part of the periphery of the sole in the operation of heel-seat fitting as usually performed.

Having described the invention, what I claim as new and desire to secure by Letters Patent of the United States is:

1. That improvement in the manufacture of shoes which consists in forming notches in the heel-seat end of a sole adjacent to the heel breast line and locating a heel with respect to the median line of the sole by inserting in said notches the lateral corners of the heel formed by the intersection of 120 the breast surface with the lateral surfaces of the periphery of the heel.

2. That improvement in the manufacture of shoes which consists in forming notches having upright corners in the heel-seat end 130

of a sole adjacent to the ends of the heel breast line, locating a heel laterally with respect to the sole by inserting the upright lateral corners of the breast of the heel in 5 said notches, and performing a trimming operation upon the notched part of the sole.

3. That improvement in the manufacture of shoes which consists in trimming the rear portion of a sole around its periphery to 10 form a convex heel-seat adapted to coact with the concavity in the heel-seat surface of the heel and providing said sole with a tongue adjacent to said heel-seat having substantially the full thickness of the sole 15 across its entire width, and applying a heel, suitably formed, to said shoe to overlie said tongue whereby the sole is held in close engagement with the upper adjacent to the breast line of the heel by the engagement of 20 the heel with said tongue.

4. That improvement in the manufacture of shoes which consists in trimming the rear portion of a sole around its periphery to form a convex heel-seat adapted to coact 25 with a concavity in the heel-seat surface of a heel, providing said sole with a tongue adjacent to said heel-seat having substantially the full thickness of the sole across its entire width at a point adjacent to the heel breast 30 line, and applying a heel recessed to a depth less than the thickness of the tongue to the heel-seat of said shoe to overlie the tongue and hold the sole closely in engagement with the upper adjacent to the breast line of the 35 heel by the engagement of the heel with said tongue.

5. That improvement in the manufacture of shoes which consists in forming a tongue upon the heel-seat end of an unfinished sole 40 extending rearwardly of the breast line of the heel, each lateral edge of said tongue forming one side of a notch the corner of which lies on a line to which the edge of the sole is to be finished, said notch being 45 adapted to receive a projecting corner of the breast of the heel, locating the heel with respect to said sole by means of said notches, and attaching it to the shoe over said tongue.

50 6. That improvement in the manufacture of shoes which consists in forming the heel end of the sole of a shoe for the reception of the heel, beveling the heel-seat of the sole to cause it to fit the concavity of the heel-seat surface of the heel, forming a tongue 55

adjacent to said beveled portion, one part of said tongue at its maximum width extending completely across the shank of the shoe, and applying a heel to said shoe which is provided with a recess below its normal 60 concavity to receive said tongue and adapted to bear against said sole approximately at the maximum width of the tongue.

7. A shoe bottom comprising an untrimmed sole and a finished heel, said sole 65 having at the rear end of its shank portion lateral extensions in the untrimmed edges of the sole arranged in conjunction with the central portion of the sole to form notches at the heel breast line to receive the outside 70 corners of the breast of the heel and to locate them with respect to the shoe bottom.

8. A shoe bottom comprising a sole and a finished heel, said sole having at the rear end of its shank portion a portion forming 75 a heel-seat surface and a rearwardly extending tongue thicker than said seat forming portion, said heel having a recess in its attaching surface shaped complementally to the tongue extending across the whole width 80 of the breast of the heel.

9. A shoe bottom comprising a sole and a finished heel, said sole having at the rear end of its shank portion a rearwardly extending tongue whose thickness at a point adjacent 85 to the heel breast line is substantially the full thickness of the sole, said heel having a recess in its heel-seat engaging surface adjacent to the heel breast, said recess being of less depth than the thickness of the 90 tongue whereby the attached heel will bear against the tongue at the heel breast line and form a tight joint.

10. A shoe bottom comprising an untrimmed sole and a finished heel, said sole 95 having at the rear end of its shank portion a rearwardly extending tongue and lateral extensions in the untrimmed edges of the sole adjacent to the sides of said tongue constructed and arranged to form notches at 100 the heel breast line, said heel having a recess shaped complementally to said tongue extending across substantially the whole width of the breast of the heel to form in conjunction with the lateral faces of the heel 105 sharp corners adapted to be received in the aforesaid notches.

In testimony whereof I have signed my name to this specification.

THOMAS C. ERSKINE.
